(57) **CLAIM**

The ornamental design for a barbecue grill, as shown and described.

DESCRIPTION

FIG. 1 is an isometric view of a first embodiment of a grill.

FIG. 2 is a front view of the first embodiment of the grill.

FIG. 3 is a right side view of the first embodiment of the grill.

FIG. 4 is a top view of the first embodiment of the grill.

FIG. 5 is a bottom view of the first embodiment of the grill.

FIG. 6 is an enlarged fragmentary view of FIG. 1.

FIG. 7 is a first enlarged fragmentary view of FIG. 2.

FIG. 8 is a second enlarged fragmentary view of FIG. 2.

FIG. 9 is an enlarged fragmentary view of FIG. 3.

FIG. 10 is a second isometric view of the grill of FIG. 1.

FIG. 11 is an enlarged fragmentary view of FIG. 10.

FIG. 12 is an isometric view of a second embodiment of the grill.

FIG. 13 is a front view of the second embodiment of the grill.

FIG. 14 is a right side view of the second embodiment of the grill.

FIG. 15 is a top view of the second embodiment of the grill.

FIG. 16 is a bottom view of the second embodiment of the grill.

FIG. 17 is an enlarged fragmentary view of FIG. 12.

FIG. 18 is a first enlarged fragmentary view of FIG. 13.

FIG. 19 is a second enlarged fragmentary view of FIG. 13.

FIG. 20 is an enlarged fragmentary view of FIG. 14.

FIG. 21 is a second isometric view of the grill of FIG. 12; and,

FIG. 22 is an enlarged fragmentary view of FIG. 21.

The broken lines in the drawings depict partial view indicia that form no part of the claimed design.
